UNITED STATES PATENT OFFICE

133,464

DESIGN FOR A BAROMETER

Charles Peckerman, New York, N. Y., assignor to
Everbest Engineering Corp., New York, N. Y.,
a corporation of New York

Application June 22, 1942, Serial No. 107,300

Term of patent 14 years

To all whom it may concern:

Be it known that I, Charles Peckerman, a citizen of the United States of America, residing at 920 Riverside Drive, Borough of Manhattan, city and State of New York, have invented a new, original, and ornamental Design for a Barometer, of which the following is a specification, reference being had to the accompanying drawing forming a part thereof, and wherein—

Fig. 1 is a front elevational view of a barometer showing my new design, and
Fig. 2 is a side elevational view thereof.

I claim:

The ornamental design for a barometer, substantially as shown.

CHARLES PECKERMAN.
